CLAIM

The ornamental design for an integrated lighting module housing, as shown and described.

DESCRIPTION

FIG. 1 illustrates a top front perspective view of a new and ornamental integrated lighting module housing;

FIG. 2 illustrates a front view thereof;

FIG. 3 illustrates a back view thereof;

FIG. 4 illustrates a left-side view thereof;

FIG. 5 illustrates a right-side view thereof;

FIG. 6 illustrates a top view thereof; and,

FIG. 7 illustrates a bottom view thereof.

Broken lines in any of included figures are for illustrative purposes only and form no part of the claimed design.

1 Claim, 6 Drawing Sheets
